UNITED STATES PATENT OFFICE.

CHARLES E. GIBBS, OF MALDEN, MASSACHUSETTS, ASSIGNOR TO PARKER BROTHERS, OF SALEM, MASSACHUSETTS.

GAME.

SPECIFICATION forming part of Letters Patent No. 617,306, dated January 3, 1899.

Application filed March 7, 1898. Serial No. 672,850. (No model.)

To all whom it may concern:

Be it known that I, CHARLES E. GIBBS, of Maplewood, Malden, county of Middlesex, State of Massachusetts, have invented an Improvement in Games, of which the following description, in connection with the accompanying drawings, is a specification, like letters and numerals on the drawings representing like parts.

10 This invention has for its object the production of a novel game, the same having as an essential part of it a plate having a projection at one or both ends, said plate being preferably shaped to resemble the outlines of 15 a turtle, the plate in this instance of my invention presenting two projections, one at each end, the projections corresponding with the head and tail of a turtle, said plate having other projections corresponding with the 20 feet of a turtle. I prefer to employ a series of these plates in the game, and they will preferably be struck up from sheet metal or other thin, rigid, stiff material, leaving the central part of the plates of concavo-convex 25 shape, so that several of said plates may be nested or stacked one upon the other to constitute what I shall designate the "first position" of the game.

I prefer to use as a part of the game a log 30 or equivalent and a stick by which to strike one of the projections of the plate to make it jump in the direction of and over the log, or, it may be, in the box, it constituting in the game a pool.

35 Figure 1 represents a top or plan view of one of the plates referred to. Fig. 2 shows six of said plates stacked in a pile as when the game is started. Fig. 3 shows the six plates arranged indiscriminately, some right side and some wrong side up, together with 40 a log, the dotted lines showing a plate jumped over the log, supposedly from the full-line position, the said box being shown as lying near the log and constituting a pool or pond; 45 and Fig. 4 shows a stick for striking the plates.

Each plate consists of a central or body portion A, concavo-convex in shape, said body portion having an end or projection a, 50 preferably upturned slightly, it representing,

say, the tail of a turtle, and a second projection b, also preferably upturned, it representing the head of a turtle, other projections 1, 2, 3, and 4 being extended from the body part A of the plate, representing feet of the turtle. These plates are preferably made of thin but yet rigid sheet metal, and they are formed by stamping or dieing them out. In the game these plates are superimposed one on the other, as in a stack, as in Fig. 2. A log, as 55 B, of considerable diameter may be laid upon a table or board, or with said log or instead of the log I may use the box, so that the plates may when struck be made to jump over the log or into or over the box. Fig. 4 shows a 60 rod or stick D, which may be of steel or metal, if desired. The player takes the rod in hand and strikes the projection a of the uppermost plate in the series stacked, as in Fig. 2, and as a result of a sharp quick blow the several 65 plates will fly in different directions, and they will land, say, as represented in Fig. 3, where the plates marked A' are supposed to be right side up and those A² wrong side up. As the plates are convex or rounded on their 70 backs, it follows that when they are in the position shown at A² they are readily locked, and therefore it is more difficult to give the turtles any desired direction by a blow, inasmuch as when the turtles are right side up 75 the legs, resting firmly on the board, form a definite fulcrum or pivot, turning of the turtles thereby enabling the player to judge with tolerable accuracy of the direction in which they will jump, according to any given blow. 80 In the game the count may be made of those which are right side up and those which are wrong side up to make points in the total score. The player then strikes the projections a of those plates which are right side 85 up and attempts to make the plates or turtles jump, either over the log or into the pool, one entitling the player to a certain count and the other to another count. The plates turned wrong side up have to be struck in 90 some way so as to reverse them, and thereafter they may be struck to make them jump in the desired direction.

The feet on the plates support them readily, so that they may be easily jumped when 100

either the projection *a* or *b* is struck by the rod *D*, as either may be, according to the direction it is desired to jump the plates. These plates may be finished by any japanning or equivalent process, and they may be of any desired or suitable color, and, if desired, they may be all of different colors.

It will be obvious that the length and size of the projections *a* or *b* might be varied without departing from my invention and that the plates might be made to jump if provided with but one of the said projections; but two are preferable, because of the greater range of control of the plates. Slightly upturning the projections referred to enables the stick to get a better hold upon the plates in order to make the blow of the stick effective in overturning the plates.

It will be observed that the projections *a* are short and are simply upturned, whereas the projections *b* are longer and are not only upturned but are slightly downturned at their extremities, the result of this construction being that when the end *a* is struck, whether with a sharp blow or a slow blow the turtle is caused to jump; but a slow blow on the projection *b* cannot possibly make the turtle jump, and any kind of a blow on the inner part or upwardly-inclined part of the projection *b* cannot cause the turtle to jump, and also because of the peculiar shape of the outer end of the projection *b* a blow thereon is more apt to make the turtle simply turn bottom side up than to make it jump, while a sharp blow on the extreme end of the projection *b* if skilfully delivered is the only kind of a blow that will make the turtle jump. As before stated, the stacking or nesting compactly together of the turtles, as shown in Fig. 2, is of considerable importance in playing the game, inasmuch as it enables a blow given, for instance, to the projection *a*, Fig. 2, to simultaneously and similarly affect all the turtles, whereas if the turtles were not so shaped as to be capable of nesting together compactly throughout their entire body-surface it is evident that a blow on the top one would simply cause that one to jog or turn away from the others without causing all the turtles to jump.

Having fully described my invention, what

I claim, and desire to secure by Letters Patent, is—

1. A game having as one of its component parts a thin plate provided with a slightly-upturned projection which may be struck a quick blow to cause the plate to jump or overturn, substantially as described. 55

2. A game having as one of its component parts a plate provided with two upturned 60 projections, one of said projections being longer than the other and the longer projection being slightly downturned at its free end, either of which may be struck a quick blow to cause the plate to jump or overturn, sub- 65 stantially as described.

3. A game having as one of its component parts a thin plate having a projection and a plurality of feet to support the plate while the projection is being struck by a stick, the 70 feet projecting in one direction and the projection in an opposite direction, substantially as described.

4. A game consisting of a plurality of plates, each having an upturned projection, and a 75 plurality of downturned feet, the bodies of said plates being concavo-convex in cross-section to enable them to be nested compactly together in a pile, substantially as described.

5. A game composed of a series of concavo- 80 convex plates each having an upturned projection, and a plurality of downturned legs, substantially as described.

6. A game composed of a series of similarly-formed concavo-convex plates, each having 85 an upturned projection adapted to be struck to overturn or make said plates jump, substantially as described.

7. A game consisting of a plurality of plates the bodies of which are similarly concavo- 90 convex in cross-section to enable them to be nested, &c. in a pile; each of said plates having a projection, which may be struck a quick blow in order to cause it to jump or overturn, substantially as described. 95

In testimony whereof I have signed my name to this specification in the presence of two subscribing witnesses.

CHARLES E. GIBBS.
